[57] CLAIM

The ornamental design for an eel securing device, as shown and described.

DESCRIPTION

FIG. 1 is a front and side perspective view of an eel securing device showing my new design ;
FIG. 2 is a side view thereof, the unshown opposite side being of identical appearance ;
FIG. 3 is a front view thereof,
FIG. 4 is a rear view thereof; and,
FIG. 5 is a top view thereof.
